US00D809586S

(12) **United States Design Patent** (10) Patent No.: **US D809,586 S**
Cazalet et al. (45) Date of Patent: ** Feb. 6, 2018

(54) **INTERCHANGEABLE EYEWEAR ASSEMBLY**

(71) Applicant: **Google Inc.**, Mountain View, CA (US)

(72) Inventors: **Peter Michael Cazalet**, Los Gatos, CA (US); **Maj Isabelle Olsson**, Sunnyvale, CA (US); **Matthew Wyatt Martin**, Ross, CA (US)

(73) Assignee: **Google LLC**, Mountain View, CA (US)

(***) Term: **15 Years**

(21) Appl. No.: **29/585,117**

(22) Filed: **Nov. 21, 2016**

CLAIM

The ornamental design for interchangeable eyewear assembly, as shown and described.

DESCRIPTION

FIG. 1 is a front perspective view of interchangeable eyewear assembly according to our design;

FIG. 2 is a front elevation view of the interchangeable eyewear assembly of FIG. 1;

FIG. 3 is a back elevation view of the interchangeable eyewear assembly of FIG. 1;

FIG. 4 is a right elevation view of the interchangeable eyewear assembly of FIG. 1;

FIG. 5 is a left elevation view of the interchangeable eyewear assembly of FIG. 1;

FIG. 6 is a top elevation view of the interchangeable eyewear assembly of FIG. 1;

FIG. 7 is a bottom elevation view of the interchangeable eyewear assembly of FIG. 1; and,

FIG. 8 is another front perspective view of the interchangeable eyewear assembly of FIG. 1.

The broken lines shown in the drawings are included for the purpose of illustrating unclaimed portions of the interchangeable eyewear assembly and form no part of the claimed design. The dash-dot lines indicate boundaries and form no part of the claimed design.

1 Claim, 4 Drawing Sheets
